MEANS FOR BUILDING DENTURES

Karl Ross, Montreal, Quebec, Canada

Application February 14, 1935, Serial No. 6,437

15 Claims. (Cl. 32—32)

The present invention pertains to a novel dental apparatus for use in setting teeth in models of the patients' gums prior to forming the final plate. The principal object of the invention is to provide such a device enabling the accurate setting or positioning of each tooth separately and maintaining it in such position until the bite for the final plates is made. Each tooth is held in its determined position by mechanical means which do not readily permit of accidental displacement. In this respect the invention presents many obvious advantages over the present method of setting and adjusting teeth directly in the dental compound. The device of the invention is also useful in making partial plates for any desired number of teeth and also for setting the teeth in the construction of other kinds of dental work such as bridge work, for example.

Another object of the invention is to provide a set-up of the teeth removable from the articulator jaws, this set-up being suitable for insertion in the mouth of the patient for try-on purposes.

Although the invention is intended primarily for practical dental work, it may also be used for demonstration work and instruction.

The invention is fully disclosed by way of example in the following description and in the accompanying drawings in which

Figure 1 is a plan view of the lower set of teeth mounted in the articulator;

Figure 2 is a perspective view of one of the incisors;

Figure 3 is a plan view of an incisor and its supporting means;

Figure 4 is a corresponding side elevation;

Figure 5 is a perspective view of the clip for holding the tooth;

Figure 6 is a section of the binding ring on the clip;

Figure 7 is a plan view of a bicuspid or molar and its supporting means;

Figure 8 is a corresponding side elevation;

Figure 9 is a plan view similar to Figure 7, showing the tooth in a different adjustment;

Figure 10 is a plan view of a modified form of rear supporting mechanism;

Figure 11 is a detail section, similar to Figure 12, showing a somewhat different adjustment;

Figure 12 is a section on the line 12—12 of Fig. 1;

Figure 13 is a side elevation of the articulator with the teeth mounted therein;

Figure 14 is a detail section of the supporting means shown in Figures 7, 8, and 9;

Figure 15 is a detail section of the supporting means for the bicuspids and molars;

Figure 16 is a plan view of a modified holding means for the incisors and canines;

Figure 17 is a perspective view of the clip thereof;

Figure 18 is a perspective view of the binding ring thereof;

Figure 19 is a cross section of the supporting means for the incisors;

Figure 20 is a bottom plan view of the apparatus for supporting the upper set of teeth;

Figure 21 is a detail section thereof;

Figure 22 is a bottom plan view of one of the bicuspids;

Figure 23 is a section on the line 23—23 of Fig. 22;

Figure 24 is an elevation of the apparatus shown in Figure 14;

Figure 25 is a detail elevation of the support for one of the incisors;

Figure 25—A is a detail perspective view of the supporting means shown in Figs. 3 and 4;

Figure 26 is a plan view of a set-up, independent of the articulator, for a try-on in the mouth and on the lower jaw;

Figure 27 is a detail perspective view of the supporting means for the incisors and canines;

Figure 28 is a section on the line 28—28 of Fig. 26;

Figure 29 is a plan view thereof;

Figure 30 is a detail rear elevation thereof;

Figure 31 is a similar view of a modified construction;

Figure 32 is a cross section of the base plate, showing in elevation one of the incisors and the supporting means therefor;

Figure 33 is a similar section taken at a different point of the base plate;

Figure 34 is a longitudinal section of one of the transverse supporting bars;

Figure 35 is a section on the line 35—35 of Fig. 34;

Figure 36 is an elevation of the transverse tie-rod;

Figure 37 is a detail longitudinal section thereof;

Figure 38 is a section on the line 38—38 of Fig. 37;

Figure 39 is a detail plan view of Figure 33;

Figure 40 is a detail sectional view at one end of apparatus shown in Figure 26;

Figure 41 is a bottom plan view of a set-up in-

dependent of the articulator, for a try-on on the upper jaw;

Figure 42 is a detail cross section thereof illustrating in elevation one of the incisors and the 5 supporting means therefor;

Figure 43 is a detail perspective view of an element used in Figure 10;

Figure 44 is a detail cross section of Figure 41, taken at the rear of the device;

10 Figure 45 is a detail plan view of Figure 44;

Figure 46 is a detail elevation of the supporting means for the incisors;

Figure 47 is a detail plan view of Figure 44;

15 Figure 48 is a perspective view of a part in Fig. 46;

Figure 49 is a detail plan section of Figure 42;

Figure 50 is a perspective view of the device shown in Figure 47;

20 Figure 51 is a detail perspective view of an end of the retaining wire shown in Figure 41;

Figure 52 is a perspective view of the securing means therefor;

25 Figure 53 is a perspective view of a modified end assembly shown in Figure 26;

Figure 54 is a perspective view of the tool for manipulating the teeth;

Figure 55 is a plan view of a plate to be attached to the device shown in Figure 10;

30 Figure 56 is a section on the line 56—56 of Fig. 55;

Figure 57 is a side elevation corresponding to Fig. 55;

35 Figures 58 and 59 are perspective views of pliers for manipulating certain tooth supporting means; and

Figures 60 and 61 are perspective views of details of the pliers.

Reference to the drawings will now be made by use of like characters which are employed to 40 designate corresponding parts throughout.

The method employed in this invention does not necessarily depend on the use of an articulating machine, though it will be thus described herein and probably its use will materially aid 45 in carrying out the method.

The initial step is one common to this art and that is making a plaster cast or plaster casts of the jaw interiors indicated by the letters A and B.

The next step is to apply a temporary sheathing on the gums to form a base plate, usually a sheet wax formed to the shapes of the plaster casts and representing the gum projections therefrom for use either within the mouth or in the articulating machine. Soft wax is now 50 built up on these base plates and the "bite" made, which gives the distance from upper to lower jaws.

The distance set, the next step is to introduce the teeth of the artificial set and to do this the 55 back teeth on each side are slidably and rockably mounted in tracks and the front teeth on index fingers and all adjusted to the shapes of the jaws and other peculiarities of the mouth for the tracks, the index fingers, the universally jointed 60 arms and other holders and tools and the rest of the parts contribute to the operations tending towards placing each tooth and holding it.

The next step is filling in the gum supports which in this operation constitutes soft wax 65 and this is done in one waxing for all the teeth on the outside for a part of the height of each tooth, then the frame of tracks, fingers and arms, may be removed and the inside filling of wax to represent gums added, also in one waxing.

70 75 Now the pattern is complete and the final oper-

ation is to cast the plates in suitable material usually a hard rubber or composition.

The articulator is better shown in Figure 13 wherein may be seen the articulator jaws A and B described in detail below. To the jaws are applied the models 2 and 3 of the upper and lower gums which are made in the usual manner. The invention is directed more particularly to the means and method of setting and applying the teeth to the gums.

10 The incisors 4 are notched at 5 on the rear surface as indicated in Figure 2, and from the bottom of the notch extend two pins 6, one above the other. The remaining teeth 7 are provided with a single removable stem 8 extending rearwardly as shown more clearly in Figures 14 and 20. It is understood however that the stem 8 could be replaced by another one in making the final plate. The second stems could be made of same material as the final plates, thus holding firmly and integrally the teeth to the denture. The object is for holding the teeth in position so they could not go out of shape before vulcanizing.

15 For supporting each of the teeth 4, there is 25 provided a member such as shown in Figures 3, 4, and 5, consisting of a ball 9 from which extends a pair of spring arms 10 with perpendicular ends 10' engageable respectively with opposite sides of the pins 6 and beneath the heads 30 6' thereof. A ring 11 is slidably mounted on each pair of spring arms and effects compression between the ends 10' by engagement with humps 12 formed in the arms. For removing the ring from the humps, in order to spread the arms, a 35 tool such as shown in Figures 58, 59, 60, and 61 may be inserted in a notch 13 cut in the ring. The ring is very small and is therefore better handled with a tool.

40 As shown in Figures 3 and 4, the ball 9 is received in a socket 14 formed on the end of a stem 15. As shown in Figure 1, these members are associated only with the incisors. Obviously, a universal joint is provided in each ball 9 and socket 14, and there is sufficient friction between these parts to maintain any given angular 45 adjustment 1. The stems 15 are received in telescopic tubes 16 which in turn are articulated on the rear plate 17 as will presently be described. The rear end of each tube 16 is disposed over a 50 slot 18 in plate 17 and is formed with ears 18' resting on a U plate 19 mounted over the slot. A bolt 20 passes through the rear end of each tube 16 and through the plate and slot to hold the parts together. The rear end of each tube 55 is split and formed with a pair of rounded ears 18' resting on the corresponding plate 19.

As shown more clearly in Figure 12, a pair of stems 21 are mounted transversely of the mouth in ears 22 formed in the plate 17, the ears being 60 tightened by bolts 22'. The purpose of the stems 21 is to support a pair of track members 23 extending along the canines, bicuspids and molars.

To support the track members, the free end of each stem 21 is split at 24 to receive a screw eye 65 25 (Fig. 15) held by a bolt 27 (Fig. 1). The free end of the screw eye threads into the rear end of the corresponding track member 23. This end of the track member is reduced and receives a collar 28 having a setscrew 29 by means of 70 which the assembly is secured at this point.

The track members 23 are nearly tubular in cross section, having an opening at the top as may be seen in Figures 8 and 19, and are curved horizontally inwardly and at the same time ver- 75

tically to follow generally the contour of the jaws. For each tooth to be carried by a track member, there is provided a pair of lugs 30 angular in shape and each having a round or tubular lower portion fitted one within the other and both within the track member. The previously mentioned stems 8 extending from the bicuspids and molars pass through a pair of lugs 30. The members of each pair of lugs are slideable relatively to each other at the tubular ends, whereby the angle of each stem 8 to the member 23 may be regulated as illustrated by a comparison of Figures 7 and 9.

Between the lugs 30, the stem 8 is surrounded by a coil spring 31 wound on a curved axis for a purpose which will presently appear. The end of stem 8 adapted for insertion in and removal from a tooth is indicated by the numeral 32 in Figure 14, and directly behind this end portion, 15 the stem is formed with a peripheral groove 33 at the hole 33' of the forward lug 30. The groove interlocks with the periphery of the hole to hold the lug 30, and the foremost coil of the spring 31 enters the groove 33, due to the curvature of 20 the axis of the spring, and thereby holds the stem 25 firmly against the lug 30.

The canines 4' have their balls 9 received in sockets 34, as shown in Figure 25. Each socket, however, has a depending stem 35 for a purpose 30 which will presently appear. Each socket 34 is mounted on a stem 36 having a loop 36' at one end in which the stem 35 is screwed. The stems 36 are attached to the track members 23 by the means illustrated in Figure 19. A ball 37 is 35 mounted in the track member and has a stud 38 vertically screwed therein. The end of the screw is pointed, and the bottom of ball 37 is split so that the screw spreads the lower part of the ball and holds the ball tightly in the track member. 40 A plate 39 is held beneath the head 38' and is formed at one end with a loop 39' enclosing the stem 36. Each stem 8 passing through a pair of lugs 30 has a ball 40 screwed on the rear end thereof for assembly and finish.

45 In the use of the invention as thus far described, the teeth are properly adjusted relatively to the gums 2 and 3 by means of the several universal joints and telescopic members. The forward surfaces are first covered with wax, 50 and then the supporting members, such as stems 8 and the clips 10, are removed, after which the rear surfaces are enclosed in wax to complete the impression of the artificial set of teeth as prepared on the articulator. The upper end and 55 lower dentures are cast up to the line 41 in Figure 2.

From the lower jaw B of the articulator extends a standard or upright 42 at a slight angle. To this member is secured a transverse shaft 43 by means of a suitable clamp 42' as better illustrated in Figures 1 and 13. A plate 44 is adjustably secured to the shaft by another clamp 43' and occupies a position between the shaft 43 and the plate 17, as may be seen in Figure 1. 60 In the ends of the plate 44 are mounted short stems 45 which in turn support the collars 46' of another plate 46. The collars permit an angular adjustment of plate 46 about stems 45. Finally, the plate 17 is adjustably secured to plate 46 by 65 means of a screw 47 mounted in a slot 47' in plate 17.

70 The upper denture attachment is shown in bottom plan view in Figure 20. The arrangement of the teeth is substantially the same as 75 in the lower denture. Tubes 16a are attached

to a plate 17a, these parts corresponding respectively to the members 16 and 17 of Figure 1. A plate 46a is substituted for the plate 46 of Figure 1, and the stems 21 of Figure 1 are replaced by angular stems 48. Each stem 48 carries a split ball 49 which in turn is received in the hollow end of a transverse shaft 50 occupying an upper position as may be seen in Figure 13. Screws 51 are inserted in the end of the shaft and are adapted to engage the balls to tighten them against the stems 41, to hold the latter in place. By means of the balls 49, the stems 48 may be adjusted angularly.

The upper jaw A of the articulator has a pair of rearwardly extending stems 53 carrying a transverse stem 54 as may be seen in Figures 20 and 21, for the purpose of supporting the shaft 50. The construction for this purpose comprises for each stem 53 a U shaped member 55 having its bottom engaged by the corresponding stem as shown more clearly in Figure 21. The shaft 50 is held in the ears 55' of the member 55. An angular piece 56 is inserted between the shaft 50 and the stem 53, and the assembly is secured by means of screws 57 threaded through the shaft 50 and bearing on the members 56. The screws also adjust the elevation of shaft 50.

The bicuspids and molars 7 have a pair of sockets 58 at the end adjacent to the gum, and the molding compound enters the sockets to hold 30 the teeth to the denture. Between the sockets there remains a ridge 58' for receiving the stem 8 as shown in Figure 23.

Figures 17 and 18 show a modification of the clip illustrated in Figures 3, 4, and 5. The bent ends 10' of Figure 5 are here replaced by straight bars 59 formed integral with the arms of the clip. The plain ring 11 of Figure 6 is replaced by the modified ring 60 shown in Figure 18. This member has a pair of projections 61 which are received between the ends 59 as may be seen in Figure 16. The other end of the ring carries a pair of curved ears or projections 62 which may be grasped by the pliers shown in Figures 58 to 61, for moving the ring from one position to another.

Figure 10 illustrates a modification of the previously described plate 44, the corresponding member being here indicated by the numeral 63, and also a modification of the member 43 which is here indicated by the numeral 64. The stems 45' in the ends of the plate 63 carry a yoke 65 adapted to carry the plate 66 shown in Figures 55, 56, and 57. For this purpose the plate 66 has a pair of stems 67 received in apertured members 68 mounted on the ends of the yoke 65. The socket members 68 are separately illustrated in Figure 43. Each socket member has a tube 69 depending from the plate 68 in line with the hole. A pair of tongues 70 are turned upwardly and tubes 69 are slidably received in slots 71 cut in the ends of the yoke 65. The vertical portions of the tubes 69 are pressed slightly inwardly for firm engagement with the stems 67 inserted therein.

The stems 67 are not integral with the plate 66, but are formed on a double plate 72 as shown in Figures 55 and 57. The plate 72 is laid over the edge of plate 66 and secured thereto by a staple 73 passing through a slot 74 formed at the center of the rear edge of plate 66. The plate 66 is also provided with holes 74' to use it on ordinary 70 articulators.

Figure 26 illustrates a mounted set of teeth independent of the articulator and forming a unit which may be tried on in the mouth. The try-on is made by mounting the set on the base plate 75

84 (Fig. 32) which fits on the gums. The try-on in the mouth is used for a final adjustment of the teeth. A similar set-up for the upper denture is shown in Figure 41.

5 In Figure 32 the incisors and canines have clips 10a as previously described received in sockets 76. From each socket extends a flat 76' received in a cradle 71, shown in perspective in Figure 27. The cradle has its lower end curved at 78 to receive a wire 79 extending along the rear of the bicuspids and molars. To the center of the cradle is pivoted a link 80 carrying a loop or ring 81 through which is passed a transverse rod 82 by which the cradle is positioned relative to 10 the rod 82. The four rear teeth on each side are supported in the manner previously described, namely by means of lugs 30 mounted in track members 83. A section of track is shown in Figure 28. One end of the track is held as shown 15 in Figures 28 and 29, while the other end is shown in Figures 33 and 39.

A bent wire 85 or metal bent thus is inserted in the track 83 and is formed externally with a ring 86. The other or outer side of the wire is 20 formed integral with a slide piece 87 in which the bent wire 88 is slidably mounted. The upper end of the wire is in the form of a finger piece 89 for adjustment. Near the member 85 is 25 an angular stem 90 having a horizontal portion 30 lying over the track as shown in Figure 29. This portion receives a vertical screw 91 passing through the track and engaging the lower horizontal end of the member 88, whereby the height of track member 83 may be adjusted. The lower 35 vertical portion of the stem 90 telescopes in a tube 92, the lower end of which is curled around the wire 79.

Figure 31 shows a modification of the slide piece of Figure 30, the wire 88 in the latter being 40 replaced by a plate 93 having a pin 94 extending therefrom. It may be seen in Figure 30 that the wire 88 is spread for frictional engagement with its slide. This slide is formed with a stop 95 adapted for engagement by a finger piece 89 to 45 prevent the wire from being pulled out of the slide.

The rear end of each track section 83 receives 50 the ball end 96 of a hook 97 having a ring 98. A transverse bar 97a has its end hooked into the 55 opposite ring 98. The ball end 96 receives one end of a U shaped wire 99 partly covered by a double tube 100 shown more clearly in Figure 39. The forward end of the tube is articulated to a curved wire 101 which in turn is pivoted to a plate 102 resting on the base plate 84. The wire 99 is adjustable lengthwise in tube 100, and the angle of elevation is adjustable by means of the articulated wire 101.

Integral with the member 97 is a depending 60 stem 103 telescoping in a tube 103', said tube being hooked around the rod 79 as clearly shown in Figure 33. The rings 86 receive ends of rod 82 in the same manner that the hooks 98 receive the 65 ends of rod 97a.

Figure 34 illustrates a section of rod 82 of 70 Figure 26, and the rod 97a is shown in elevation in Figure 36. The rod 82 contains a slidable tube 82a, having a hook 82b formed on its exposed end. The tube 82a receives the slidable stem 82c having a hook 105 on its exposed end. A lock plate 106 slidable on the stem adjacent to the hook is adapted to close the hook. The inner end of tube 82a is flanged inward at 82b, and the inner end of stem 82c is bent outward at 75

82d, so that the members 82a and 82c cannot be pulled apart.

The rod 97a is likewise telescopic, having an inner piece 97b with a hook 105' formed on its outer end. Adjacent to this hook is a sliding lockplate 106' as previously described. The inner end of the outer telescopic member has a notch 107 in which is received a spring ring 108. The inner end of the stem 97b is grooved at 107' to receive a portion of spring ring 108 and prevent the member 97b from being pulled out of member 97a. The hooks 82b and 104 have such a curvature that they cannot be removed from their respective anchoring rods when the hooks 105 and 105' are locked. 15

The ends of track sections 83 are substantially tubular as shown in Figure 40 and are each closed by a plate 109 carrying an integral ball 109' sprung into the end of the track section, so that there will be no exposed rough ends to injure 20 the mouth of the patient.

In addition to the plate 102 for holding the assembly on the base plate 84, auxiliary plates 110 are mounted on the wires 79 wherever there is space for them. Also, there are provided additional members 111 functioning like the parts 90, 92 and 103, 103', joining the track 83 to the wire 79. The members 111 are fitted in ball members, similar to the ball ends 96, mounted in the track section. The wires 79 have telescopic 30 tubes 112 at the rear ends for extension. 25

To prevent the teeth from falling out, they are encircled by an outer wire ring 113, one end of which is shown in Figure 51. The parts for holding the ends in the track section 83 are illustrated in Figure 52. The assembly for each end includes a cylindrical plug 114, a curved plate 115 and a screw 116 adapted to be threaded into both parts. The cylinder or plug 114 is mounted in the track, and over it is placed the curved plate 115. Finally, the screw 116 is inserted in both parts, and the hook end of wire 113 is hooked around the screw. The screw is then tightened to bind the parts together. 35

A slightly different form of wire 113' is shown 40 in Figures 51 and 41. A doubled wire 117 is inserted in a plug 118 which, in turn, is attached to the end of wire 113' by a set-screw 118'. The double wire is fastened to the track by the means shown in Figure 52 and described in connection 45 therewith.

The similar apparatus for the upper denture, independent of the articulator, is shown in Figure 41. The incisors and canines are articulated on universal joints, including each a socket 119. 50 Figure 42 shows the socket member for the canines, and Figure 46 for the incisors. With reference first to Figures 46 and 48, a flat stem 120 extends from the socket member. In a hole 120' in the upper end of the member 120 is inserted one end of a short stem 121 having a head 122 and telescoping in a tube 123. The tube terminates in a ball 124 pivotally received in a tubular member 125 formed integral with or secured to another tubular member 126. The parts 124 and 125 form a double or twin tube. In Figures 42 and 49 the stem 127 extending from socket 119 is also flat and is surrounded near its upper end by one end of a stem 128 telescoping in a tube 129 corresponding to the tube 123 55 60 65 70 of Figure 46.

The ends of the transverse tie rod 130 of Figure 41 are held in the device shown in Figures 47 and 50 which enables adjustment to any desired angle or height. This device embodies end 75

plates 131 and 131' fixed to the base plate 132 shown in Figure 44. The plate 131 has a pivot pin 133 terminating in a hook to which is articulated a double tube 134. Stems 135 slide in the 5 double tube and are pivotally attached to one end of a center member 136. The other end plate 131' has a pair of ears 131a in which slides a hook 137. To this hook is articulated a strap 137' which is also suitably hinged to the center 10 member 136. The inner edge of the end plate 131 is curled to form a tube 138 for receiving the end of the wire 79' corresponding to the wire 79 of Figure 26.

The center member 136 is formed with a socket 15 140 which is received in the corresponding track section 83. To each end of the tie-rod 130 is attached an ear 141 to which in turn is hinged a plug 142 receivable in the socket 140.

The ends of tracks 83 in Figure 41 are provided with extension tracks 143 closed by plates 20 144 so that there will be no exposed rough ends to injure the mouth of the patient.

Figure 54 shows in perspective a tool 150 for holding the teeth and putting them in place. 25 One jaw of the tool has a socket 151 and is split from the socket at 152. This jaw is of varying width and carries a sliding clip 153. By this means the width of the socket may be varied for different sizes of teeth.

30 The pliers for manipulating the previously mentioned rings 11 and 60 are shown in Figures 58 to 61. This tool comprises a pair of jaws 155 pivoted together at 156. Between the jaws is inserted a flat spring 157 coiled at 158 and 35 adapted to hold the pressure ends of the jaws apart. Between the same ends of the jaws is also inserted a sliding spreader 159 for establishing any given pressure between the working ends 160 of the tool.

40 It may now be seen that the invention provides universally adjustable supports for the teeth whereby the latter may be set in any desired position before being fixed in the denture, whereby the previously mentioned objects of the invention are fulfilled by this means and by the various devices previously described in detail.

Although specific embodiments of the invention have been illustrated and described, it will be understood that various alterations in the 50 details of construction may be made without departing from the scope of the invention, as indicated by the appended claims.

What I claim is:—

1. In a dental apparatus, track members, supports mounted in said members and individually adjustable therein, each support including a pair of lugs slidable relatively to each other, and a stem passed through each pair of lugs and adapted for the mounting of a tooth thereon.

60 2. In an articulator, track members, supports mounted in said members and individually adjustable therein, each support including a pair of lugs slidable relatively to each other, a stem passed through each pair of lugs and adapted 65 for the mounting of a tooth thereon, and a spring on each stem and between the lugs.

3. In an articulator, a standard, individual tooth supports for the frontal teeth supported from said standard, universally adjustable means embodied in each of said supports, track members for the lateral teeth, supports mounted in said members and individually adjustable therein, each support including a pair of lugs slidable 70 relatively to each other, and a stem passed

through each pair of lugs and adapted for the mounting of a tooth thereon.

4. In an articulator, a standard, a plate supported therefrom, telescopic rods adjustably attached to said plate, and extending toward the 5 positions of the frontal teeth, clips universally joined to said rods and adapted for attachment to artificial teeth, track members for the lateral teeth, supports mounted in said members and individually adjustable therein, each support, including a pair of lugs slidable relatively to each other, and a stem passed through each pair of lugs and adapted for the mounting of a tooth thereon.

5. In an articulator, a standard, a plate supported therefrom, telescopic rods adjustably attached to said plate, and extending toward the 10 positions of the frontal teeth, clips universally joined to said rods and adapted for attachment to artificial teeth, track members for the lateral teeth, supports mounted in said members and individually adjustable therein, each support, including a pair of lugs slidable relatively to each other, and a stem passed through each pair of lugs and adapted for the mounting of a tooth thereon.

15 6. In an articulator, a standard, a plate supported therefrom, telescopic rods adjustably attached to said plate, and extending toward the positions of the frontal teeth, clips universally joined to said rods and adapted for attachment to artificial teeth, track members for the lateral teeth, supports mounted in said members and individually adjustable therein, each support, including a pair of lugs slidable relatively to each other, and a stem passed through each pair of lugs and adapted for the mounting of a tooth thereon, and a ball mounted in said track member for supporting a plate having at one end a loop for enclosing the end of a stem, said stem having a loop at the other end for receiving a 20 stem integral of a socket, clips universally joined to said socket and adapted for attachment to the canines artificial teeth.

25 7. In means for building dentures, a setting frame flexibly mounted and having index fingers adjustably holding the front artificial teeth, tracks transversely adjustable and pivotally mounted on said frame holding the back and intermediate artificial teeth for individual placing and positioning and a support for the frame.

30 8. In means for building dentures, a setting frame flexibly mounted and having index fingers adjustably holding the front artificial teeth, tracks transversely adjustable and pivotally mounted in said frame, track members in pairs carrying a stem projecting horizontally outward 35 from said track and adapted for the mounting of a tooth thereon.

40 9. In means for building dentures, a setting frame flexibly mounted and having index fingers adjustably holding the front artificial teeth, tracks transversely adjustable and pivotally mounted on said frame, track members in pairs carrying stems for the mounting of the back and intermediate artificial teeth and adapted for radial and rotary adjustment of the teeth relative 45 to the track.

50 10. In means for building dentures, a setting frame flexibly mounted and having index fingers adjustably holding the front artificial teeth, tracks transversely adjustable and pivotally mounted on said frame, track members in pairs carrying stems for the mounting of the back and intermediate artificial teeth, a spring about said stem and between said track members, said stem and tooth being radially and rotatably adjustable against the tension of said spring and held thereby.

55 11. In means for building dentures, a main support suitably anchored, telescopic fingers slidably mounted on said support, spring clips swivelly mounted on the upper end of said fingers for adjustably holding the front artificial teeth and tracks adjustably supported and locked in said main support and universally holding the back 60

65 70 75

and intermediate artificial teeth for individual placing and positioning.

11. In means for building dentures, a main support suitably anchored, telescopic fingers slidably mounted on said support, spring clips swivelly mounted on the upper end of said fingers for adjustably holding the front artificial teeth and tracks adjustably supported from said main support and swivelly holding the back and intermediate artificial teeth for individual placing and positioning.

12. In means for building dentures, a main support suitably anchored, telescopic fingers slidably mounted on said support, spring clips swivelly mounted on the upper end of said fingers for adjustably holding the front artificial teeth, tracks adjustably supported from said main support and swivelly holding the back and intermediate artificial teeth for individual placing and positioning and telescopic spacing members between said tracks at their ends.

13. In means for building dentures, a main support, side tracks adjustably supported from said main support and swivelly holding the back and intermediate artificial teeth, a telescopic spacing

member between said tracks, telescopic arms slideable in said spacing member and connected at their forward end to telescopic fingers, slidably mounted on said main support and spring clips swivelly mounted on the upper end of said fingers for adjustably holding the front artificial teeth.

14. In means for building dentures, a setting frame flexibly mounted and having index fingers adjustably holding the front artificial teeth, a wire mounted on said frame and encircling said teeth, and tracks swivelly holding the back and intermediate artificial teeth for individual placing and positioning and a support for the frame, and means for adjusting the wire towards or away from the back and intermediate teeth.

15. In means for building dentures, a support, a track member carried by the support, said track member having opposing sides, a tooth support comprising two lugs each adapted to bear against a side of the track member, a spring for urging said lugs into engagement with the sides of the track and a pin carried by the side lugs for supporting the tooth.
